UNITED STATES PATENT OFFICE.

SOPHIE E. DAVIS, OF CLEVELAND, OHIO.

WASHBOILER ATTACHMENT.

SPECIFICATION forming part of Letters Patent No. 654,442, dated July 24, 1900.

Application filed October 21, 1899. Serial No. 734,283. (No model.)

To all whom it may concern:

Be it known that I, SOPHIE E. DAVIS, a resident of Cleveland, in the county of Cuyahoga and State of Ohio, have invented certain new and useful Improvements in Washboiler Attachments; and I do hereby declare the following to be a full, clear, and exact description of the invention, such as will enable others skilled in the art to which it pertains to make and use the same.

My invention relates to improvements in washboiler attachments.

The object of this invention is to provide a washboiler with an attachment whereby the wash can be partially wrung before removing it from the boiler, so as to avoid spattering of water around the boiler and over the stove or heater upon which the wash is boiled.

With this object in view, and to the end of realizing other advantages hereinafter appearing, the invention consists in certain features of construction and combinations of parts hereinafter described, and pointed out in the claims.

25 In the accompanying drawings, Figure I is a top plan, partly in section, of a washboiler and attachment embodying my invention. Fig. II is a side elevation, mostly in central vertical section, on line II II, Fig. I. Fig. III is an end elevation, in transverse section, on line III III, Fig. I, looking in the direction of the arrow. Fig. IV is a top plan of the boiler's end portion that bears my improved attachment. Fig. V is a left-hand side elevation, 30 partly in section, relative to Fig. IV. Figs. IV and V show the parts on a larger scale than the preceding figures.

Referring to the drawings, *a* designates a washboiler, within which the wash is boiled 40 and thereupon partially wrung and removed from the boiler by my improved attachment into a receptacle *b*, that is hung upon one side of the boiler. Receptacle *b* in the case illustrated is provided at its upper end and 45 upon one side with two hooks *b' b'*, arranged a suitable distance apart and engaging the upper edge of the receptacle-supporting side of the washboiler. The receptacle *b* is therefore removably supported from the boiler.

50 My improved wash-wringing and wash-removing attachment for washboilers comprises

a bracket *c*, that is supported, preferably, from an end of the boiler in any approved manner. Preferably the said bracket is removably supported from the boiler, and consists of a metallic plate that engages the outer side of the upper portion of the bracket-supporting end of the boiler and is provided at its upper and inner side with two hooks *c' c'*, that are arranged a suitable distance apart and engage the upper edge and overlap the inner side of the said end of the boiler. Bracket *c* at its upper end is provided with a horizontally-arranged box *c²*, that is preferably integral with the bracket and arranged longitudinally of the boiler. The box *c²* affords bearing for a short tubular shaft *d*, that is arranged horizontally and longitudinally of the boiler, and has its inner end terminating a short distance from the inner side of the bracket-bearing end of the boiler. The shaft *d* is provided at its outer end with a crank *d'* for turning the shaft. The shaft *d* has its inner end provided with a laterally-projecting flange or arm *d²*, that affords bearing for a 75 stick or rod *e*, that is employed in elevating wash from within the boiler and participates also in the wringing of the wash preparatory to the latter's removal from the boiler. The manner of operating the stick or rod *e* will 80 hereinafter appear.

A stick or rod *f* has bearing and is freely rotatable within the hollow shaft *d*. The member *f* is arranged, therefore, horizontally and longitudinally and centrally of and a 85 short distance above the boiler. The member *f* is shiftable endwise and is preferably long enough to nearly extend the entire length of the boiler when it is shifted inwardly the maximum distance.

The stick or rod *e* is preferably long enough to render it capable of reaching into the lower portion of the boiler. The flange or arm *d²* is slotted laterally, as at *d³*, to accommodate the extension therethrough of the member *e*. 95 The slot *d³* extends transversely of the flange or arm and is wider than the engaging stick or rod *e* in a vertical direction, so as to accommodate the tilting of the latter in every direction, as well as the shifting of the same laterally endwise of the slot. The stick or rod *e* can therefore be tilted in a vertical as well 100

as in the lateral direction, and should be long enough to render it capable of reaching the wash next to the bottom of the boiler. The wash when it is boiled sufficiently is lifted 5 from the boiler by means of the stick or rod *e*, and when the latter has been lifted into a plane parallel or approximately parallel with the freely-rotatable rod *f* is locked in any approved manner to the shaft *d* against tilting 10 inwardly toward the stick or rod *f*, so that a rotation of the said shaft by means of the crank *d*' shall revolve the stick or rod *e* around the stick or rod *f*, and thereby wring the wash before the latter is removed from the boiler, 15 and when the wash has been sufficiently wrung to prevent spattering of water over and around the boiler in removing the said wash from the boiler the stick or rod *e* is loosened relative to the shaft, so that it can be tilted laterally, 20 as required, to remove the wash into the receptacle *b*. The endwise shiftability of the stick or rod *f* permits the removal of the same from the wash that has been wrung, so as to leave the wash supported from the stick or 25 rod *e* preparatory to the removal of the wash to the receptacle *b*.

The means employed for preventing an inward tilting of the stick or rod *e* toward the stick or rod *f* comprises, preferably, a vertically-tilting latch *h*, that is pivoted horizontally at one end, as at *h*', to the arm or flange *d*² at one end of the slot *d*³ at the outer side of the arm or flange and is adapted to be tilted over and transversely of the stick or 30 rod *e* and hold the latter against the inner side wall of the slot *d*³. The free end of the latch is provided, preferably, with a lateral perforation *h*², that in the operative position of the latch registers with a corresponding 35 perforation or hole *d*⁴, formed in the arm or flange *d*², and a pin *l* is inserted in the said holes in the latch's operative position and secures the latch in the said position. Upon withdrawing this pin from the perforation 40 or hole *d*⁴ the latch is free to be swung out of engagement with the stick or rod *e*. Preferably the inner wall of the slot *d*³ is provided with two recesses *d*⁵ *d*⁶, arranged a suitable distance apart and extending transversely of the 45 wall, and the latch upon its inner side is provided with two corresponding recesses *h*³ *h*⁴, arranged a corresponding distance apart and extending transversely of the latch, and the arrangement of parts is such that each recess *h*³ in the latch will register with a recess *d*⁶ in the inner wall of the slot in the operative position of the latch, and the stick or rod *e* when it engages two registering recesses *h*³ and *d*⁵ in the operative position of the latch 50 is held against lateral as well as endwise displacement. The capability of the stick or rod *f* to freely turn during the wringing of the clothes avoids undue straining of or injury to the rods or sticks *e* and *f* during the wringing operation.

I would have it understood that my invention is not limited to the details of construction hereinbefore disclosed, but embraces, broadly, a wash-wringing device comprising a hollow or tubular shaft, a box affording bearing for the said shaft, a stick or rod extending through and shiftable endwise of the said box, and another suitably-supported rod or stick arranged a suitable distance from and revoluble around the first-mentioned stick or rod. 70

What I claim is--

1. A wash-wringing attachment for wash-boilers, comprising a bracket provided, at its upper end, with a box; a tubular and suitably-operated shaft having bearing within the said box; an endwise-shiftable stick or rod extending through and freely turnable within the shaft; a flange or arm formed upon the inner end of the shaft; a stick or rod having bearing within the said flange or arm and tilt-able vertically and laterally, and means for preventing an inward tilting of the last-mentioned stick or rod toward the other rod or stick, substantially as and for the purpose set 90 forth.

2. A wash-wringing attachment for wash-boilers, comprising a bracket provided with a box; a tubular or hollow shaft having bearing within the box and provided with means for rotating the shaft; an endwise-shiftable stick or rod extending through and freely rotatable within the hollow shaft; a flange or arm formed upon the inner end of the shaft and having a lateral slot; an endwise-shiftable 100 stick or rod extending through and having bearing upon the inner wall of the said slot, which last-mentioned stick or rod is capable of being actuated into a position parallel with the first-mentioned stick or rod and is capable of being tilted vertically and laterally, and means for preventing an inward tilting of the tilttable stick or rod toward the other rod or stick, substantially as and for the purpose set forth. 110

3. A wash-wringing attachment for wash-boilers, comprising a bracket provided with a box; a tubular or hollow shaft having bearing within the box and provided with means for rotating the shaft; an endwise-shiftable stick 115 or rod extending through and freely rotatable within the hollow shaft; a flange or arm formed upon the inner end of the shaft and having a lateral slot; an endwise-shiftable stick or rod extending through and having bearing within the said slot, which last-mentioned stick or rod is capable of being tilted vertically and laterally; a latch pivoted to the aforesaid flange or arm at one end of the slot and arranged to render it capable of being 120 tilted over and upon the tilttable stick or rod, and means for locking the said latch in its operative position.

4. A wash-wringing attachment for wash-boilers, comprising a bracket provided with a 130

box; a tubular or hollow shaft having bearing within the box and provided with means for rotating the shaft; an endwise-shiftable stick or rod extending through and freely rotatable within the hollow shaft; a flange or arm formed upon the inner end of the shaft and having a lateral slot and a pin-receiving hole; an endwise-shiftable stick or rod extending through and having bearing upon the inner wall of the said slot, which last-mentioned stick or rod is capable of being tilted vertically and laterally; a latch pivoted to the aforesaid flange or arm at one end of the slot and arranged to render it capable of being tilted transversely of the tilttable stick or rod, which latch has a hole formed in its free end and arranged to register with the pin-receiving hole of the latch-bearing flange or arm when the latch is in its operative position, and a pin for engaging the said holes, substantially as and for the purpose set forth.

5. A wash-wringing attachment for wash-boilers, comprising a bracket provided with a box; a tubular or hollow shaft having bearing within the box and provided with means for rotating the shaft; an endwise-shiftable stick or rod extending through and freely rotatable within the hollow shaft; a flange or arm formed upon the inner end of the shaft and having a lateral slot whose inner wall is provided with a recess d^5 extending transversely of the said wall; an endwise-shiftable stick or rod extending through and having bearing within the said slot; which last-mentioned stick or rod is capable of being tilted vertically and laterally; a latch pivoted to the aforesaid flange or arm and arranged to render it capable of being tilted transversely of the tilttable stick, which latch has a recess h^5 arranged to register with the aforesaid recess d^5 in the operative position of the latch, and means for securing the latch in its operative position, substantially as and for the purpose set forth.

45. 6. A wash-wringing attachment for wash-boilers, comprising a bracket c having the hooks $c' c'$ and the box c^2 ; the tubular or hollow shaft d provided with the arm or flange d^2 that has the lateral slot d^3 ; the stick or rod e extending through the said slot and capable of being shifted endwise and tilted vertically and laterally; means for preventing an inward tilting of the said stick or rod toward the other rod or stick, and an endwise-shiftable stick or rod extending through and freely turnable within the hollow shaft, all arranged and operating substantially as shown, for the purpose specified.

7. The combination with the washboiler: 60 of a hollow shaft suitably supported from the boiler and extending over the chamber of the boiler; a stick or rod extending through and freely turnable within the said shaft; another stick or rod connected with the shaft and capable of being arranged longitudinally

of and parallel, or approximately parallel, with the first-mentioned stick or rod and having such connection with the shaft as to render it capable of being tilted vertically and laterally, and means for preventing an inward tilting of the tilttable stick or rod toward the other rod or stick, substantially as and for the purpose set forth. 70

8. The combination with the washboiler; a hollow shaft suitably supported from the boiler and extending over the chamber of the boiler; an endwise-shiftable stick or rod extending through and freely turnable within the said shaft; another stick or rod connected with the shaft and capable of being arranged longitudinally of and parallel, or approximately parallel, with the first-mentioned stick or rod and having such connection with the shaft as to render it capable of being tilted vertically and laterally, and means for preventing an inward tilting of the tilttable stick or rod toward the other rod or stick: of a receptacle arranged outside of, and removably attached to, the boiler, and having such arrangement relative, to the tilttable rod or stick, that the latter is capable of being tilted over the said receptacle. 80

9. The combination with a washboiler: of a bracket removably attached to the boiler and provided with a box above the boiler, a 95 tubular shaft having bearing in the said box and extending over the chamber of the boiler; an endwise-shiftable stick or rod extending through and freely turnable within the hollow shaft; a flange or arm formed upon and projecting laterally of the inner end of the shaft; another stick or rod having bearing within the said flange or arm and tilttable laterally and vertically, and capable of being arranged parallel or approximately parallel 100 with the first-mentioned stick or rod, and means for preventing an inward tilting of the tilttable stick or rod toward the other rod or stick, substantially as and for the purpose set forth. 105

10. The combination with a washboiler: of a bracket removably attached to the boiler and provided with a box above the boiler; a 110 tubular shaft having bearing in the said box and extending over the chamber of the boiler; an endwise-shiftable stick or rod extending through and freely turnable within the hollow shaft, and another stick or rod revoluble about the first-mentioned stick or rod and suitably supported from or connected with 115 the aforesaid shaft, substantially as and for the purpose set forth. 120

11. A wash-wringing attachment for wash-boilers, comprising a bracket provided with a box; a tubular or hollow shaft having bearing within the said box and provided with means for rotating the shaft; an endwise-shiftable stick or rod extending through the said shaft, and another stick or rod revoluble around the first-mentioned rod or stick and 130

suitably supported from or connected with the aforesaid shaft, substantially as and for the purpose set forth.

12. A wash-wringing attachment for wash-boilers, comprising a tubular or hollow shaft; a box affording bearing for the said shaft, and means for attaching the box to a wash-boiler; a stick or rod extending through and freely rotatable within the box, and another

rod or stick revoluble around the first-mentioned stick or rod, substantially as and for the purpose set forth.

Signed by me at Cleveland, Ohio, this 19th day of September, 1899.

SOPHIE E. DAVIS.
